(57) **CLAIM**

The ornamental design for cradle for personal digital assistant, as shown and described.

DESCRIPTION

FIG. 1 is a front perspective view of a cradle for personal digital assistant according to the present invention;

FIG. 2 is a front elevational view thereof;

FIG. 3 is a right elevational view thereof;

FIG. 4 is a rear elevational view thereof;

FIG. 5 is a front perspective view of a cradle for personal digital assistant according to the present invention, connected to a personal digital assistant;

FIG. 6 is a front elevational view thereof;

FIG. 7 is a right elevational view thereof; and,

FIG. 8 is a rear elevational view thereof.

The broken line showing of a personal digital assistant is for illustrative purposes only and forms no part of the claimed design.
